[57] ABSTRACT

An elongated actuator is arranged for rocking between a pair of rails defining a generally horizontal path. Therein, the actuator is pivotally connected, off-center from its opposed ends, to an output member which is constrained for reciprocation in a vertical course extending transversely of the path. Displacement of the output member is effected by rocking the opposed ends of the actuator into bearing association with inner path defining surfaces of the rails.

ELECTRODYNAMIC AGGREGATE MOTION POSITIONING

FIELD OF THE INVENTION

The present invention relates to displacement. Particularly, it relates to linear displacement through aggregate motion. Specifically it relates to an aggregate motion positioner for effecting stepwise movement to any selected lineal positions.

It is an object of the invention to provide an improved linear displacement system.

It is another object of the invention to provide a novel aggregate motion device and method.

It is a further object of the invention to selectively vertically displace a type carrier in a typewriter or the like.

SUMMARY OF THE INVENTION

To effect the foregoing, and other objects of the invention which will become apparent from the ensuing detailed description of the invention, an aggregate motion positioner has path defining means. An elongated actuator is associated with the path for relative movement. An output member, which has a plurality of positions of linear displacement is pivoted off-center to said actuator. Means are provided for rocking the actuator to displace the output member; and means are provided for limiting displacement of the output member as a function of the relative location of the actuator along the path.

From another aspect, the foregoing objects are achieved in an impact printer wherein printing dies are arranged in parallel columns and parallel rows which intersect said columns on a carrier supported from a stem constrained for vertical reciprocation. Means for aligning a row containing any selected die at a printing station by moving the stem vertically comprises an actuator arm having opposed end portions which are aligned transversely of the stem. Pivoting means connect the stem to the actuator arm off-center from the opposed end portions thereof. A pair of inductance coils coupled in a magnetic flux field are adapted to drive the opposed end portions upwardly and downwardly into engagement with a pair of vertically spaced apart rails.

BRIEF DESCRIPTION OF THE DRAWINGS

In the ensuing detailed description of the invention, reference is had to the accompanying drawings in which:

FIG. 1 is an elevational view of a mechanism in a printer embodying one form of the present invention, parts being broken away for the purpose of illustration;

FIG. 2 is a sectional view according to the line 2—2 in FIG. 1;

FIG. 3 is a sectional view according to the line 3—3 in FIG. 1;

FIG. 4 is a scheme illustrating the levels of displacement for which said embodiment is adapted, spacing of abutment members being exaggerated;

FIG. 5 is an elevational view of another embodiment of the invention, a plurality of alternate conditions of an actuator being shown in dashed lines; and

FIGS. 6-13 are schematic views illustrating further alternate conditions of the embodiment shown in FIG. 5, yet further alternate conditions being shown in dashed lines.

DETAILED DESCRIPTION OF THE INVENTION

Referring now more particularly to FIG. 1, shown is only sufficient of a percussive or impact printer 10 of a class generally associated with typewriters, teleprinters, and the like, for illustrating the invention. The printer comprises a type support assembly having a type carrier 14 and a depending stem 16 on the upper end portion of which the carrier is supported concentrically of the longitudinal axis of said stem. The stem is vertically oriented being constrained for reciprocation vertically through, and rotational about its longitudinal axis in, a horizontal flange or shelf 13 of a frame or carriage 12.

Carrier 14 may be conventional, being fashioned as a barrel or cylinder. On its exterior surface a plurality of printing dies are arranged in a plurality of equally spaced apart vertical columns *a*, *b*, *c*, *d*, and *e* four equally spaced apart horizontal rows I, II, III, and IV which extend in a circle about the carrier and intersect the columns.

To rotate carrier 14 about the longitudinal axis of stem 16, a pair of opposed parallel gear racks 18 and 20 are supported above flange 13 for reciprocation to and fro in a horizontal plane transversely of the axis of said stem. The gear racks operably mesh with a pinion 22 in a pair of positions spaced apart 180°. The stem, in turn, is constrained for rotation with the pinion, the hub of which has a bearing extension 23 slidable on the upper surface of flange 13. Thereby, upon extension of gear rack 18 toward the viewer (with respect to FIG. 1) and retraction of gear rack 20 away from the viewer, carrier 14 will rotate clockwise as viewed from the top. Reversal of the direction of movement of said racks will result in rotation of carrier 14 counterclockwise. The movement of gear racks 18 and 20 may be controlled in a known manner for aligning a die in any selected of the columns *a-e* with a printing station for percussive transfer of its image by known means to a web (not shown).

Vertical displacement of carrier 14 for aligning any selected of rows I-IV with the printing station is effected through the agency of an arm or rod 24. It is constrained for reciprocation vertically through a pair of horizontally spaced apart flanges 25 and 27 of carriage 12 which are disposed below flange 13. Said rod has a vertical aspect which is coaxial with and disposed below stem 16 to which said rod is coupled. For that purpose rod 24 may have a bifurcated upper off-set flange between tines 26 and 28 of which a depending reduced end portion 30 of stem 16 is rotatably engaged enabling initial angular adjustment of carrier 14. A lock nut 32 mounted on the outermost threaded end part 34, of reduced end portion 30 completes a releaseable securance. In consequence thereof stem 16 and rod 24 may be reciprocated in a vertical course as a discrete output construction or member, generally designated 35. By means which will be disclosed in ensuing description, output member 35 can be controlled to provide selected levels of output for correspondingly displacing carrier 14.

The means defining a printing station may be conventional. That is to say, it can be stationary relative to which a web (not shown) is arranged for movement; or it can advance successively for printing on a web which is immobilized horizontally. Printer 10 is of the latter type, carriage 12 being adapted for sliding movement horizontally through a succession of equally spaced apart steps. Such movement is shown as being effected by a pair of opposed bearings 36 and 38 which are connected to flanges 25 and 27 for moving carrier 14. Means for driving carriage 12 and accordingly carrier 14 transversely of the vertical course of member 35 to successive printing stations may be conventional; and as said driving means forms no part of the present invention, it is omitted from the drawings.

Means for controlling the vertical level of output member 35, and accordingly, displacement of carrier 14, comprises an actuator or actuator arm or lever 40. It has a pair of lever sections 41 and 43 with opposed outer end portions 42 and 44 which are aligned transversely of output member 35. The end portions 42 and 44 are each free to move, independently of each other, toward and away from a reference plane (such as P in FIG. 1) perpendicular to the axis of movement of the type carrier 14, or other work piece to be positioned. A pivot 46 rockably connects the actuator arm and the output member off-center from opposed outer end portions 42 and 44 and separates sections 41 and 43.

The extent or range of rocking movement of actuator arm 40 is limited by a pair of opposed horizontal rails or elongated stops 47 and 48. They define a path in which said actuator arm is disposed, the path extending transversely of the course of vertical reciprocation of output member 35. A pair of like proportioned cylindrical, preferably non-magnetic, abutment members 50 and 52 are secured to end portions 42 and 44, respectively, for engaging rails 47 and 48, thereby to limit angular movement of actuator arm 40 in opposite directions about pivot 46 by limiting movement of each end portion 42 and 44. Abutment member 50 is shown as being twice the distance from pivot 46 as is abutment member 52. Thereby, section 41 is effectively twice as long as section 43.

As a result of the foregoing arrangement, output member 35 can be displaced vertically to any selected of four conditions or levels in which the level of pivot 46 will be correspondingly disposed. These levels and corresponding aspects of actuator arm 40 are designated w, x, y, and z in FIG. 4 which illustrates all four displacement conditions, as follows: When the actuator arm is in its "w" aspect, lying parallel to and adjacent the upper rail 47, both abutment members 50 and 52 engage rail 47 for moving the output member to its highest level. With actuator arm in its "x" aspect (the position of FIG. 1), abutment member 50 is engaged with the lower rail 48, while abutment member 52 is engaged with the upper rail 47, whereby the output member is displaced to its second highest vertical level. In the second lowest vertical or "y" level of displacement, the aspect of the actuator arm is such that abutment member 50 engages the upper rail 47 and abutment member 52 engages the lower rail 48. The lowest displacement or "z" level of the output member is produced by adjusting actuator arm 40 such that it is parallel to and adjacent the lower rail 48, both abut-

ment members 50 and 52, then being in engagement with said last rail.

In accordance with the present invention, means are adapted for magnetomotively rocking actuator arm 40, particularly, reversibly driving end portions 42 and 44. Said means comprise a pair of like proportioned electrical coils 54 and 56 which are rigidly secured on end portions 42 and 44, respectively. Each of the coils 54 and 56 has a planar p profile, being wound in a rectangular configuration with a lower strand section 60, an upper strand section 62, parallel to said lower strand section, and a pair of parallel side strand sections 64 and 66, said side strand sections being substantially parallel to each other and normal to strand sections 60 and 62. In the illustrated arrangement, each of the abutment members 50 and 52 has a slot 58 (FIG. 2) to provide a seat in which the lower strand section 60 of the corresponding of the coils 54 and 56 is engaged.

The driving means for actuator arm 40 also comprises a magnetic flux field, whose lines of flux extend across a non-magnetic or air gap 68 (FIG. 2) of a permanent magnet structure 70. Each strand section 60 is coupleably disposed in said air gap with its strands extending perpendicularly to the magnetic lines of flux in said air gap. A pair of parallel elongated horizontally extending sections 72 and 74, which comprise structure 70, are oppositely polarized, extend longitudinally of rails 47 and 48 transversely of output member 35, and therebetween define said air gap. By placing each coil strand 62 outside of air gap 68, signals through coils 54 and 56 can induce magnetic fields about strands 60 for operatively driving end portions 42 and 44 of the actuator for displacing output member 35.

In the exemplary embodiment (FIG. 1) magnetic section 74 extends between the flanges 25 and 27 transversely of output member 35 through a pocket 76 in carriage 12. Upper and lower surfaces of which said magnetic section provide or carry a pair of tracks along which bearings 36 and 38 are slideable. Omitted from the drawing is a driver (which may be of known construction) for generating signals in coils 54 and 56 for producing desired angular aspects of actuator arm 40.

In the embodiment of the invention illustrated in FIGS. 5-13, sections 141 and 143 of an actuator arm 140 are preferably of unequal effective lengths, as shown. However, they need not be, provided that rails 147 and 148 have inner curved surfaces or stops 149 and 151. Herein said surfaces are convex; the curves being generated on equal radii. These curved surfaces or stops comprise means for limiting the linear displacement of output member 135 as a function of the relative position of actuator or actuator arm 140 along the path defined by said rails and transversely of the course of reciprocation of the output member. In accordance with the invention, the output member and the rail pair are arranged for relative adjustment longitudinally of a path extending perpendicularly of the course of the output member. Moreover, the curved rails may be arranged for adjustment, each relative the other thereof, whereby the range and spacing of output or displacement levels may be adjusted.

In the state of adjustment shown in FIG. 5, in which rails 147 and 148 and output member 135 are "centered," the centers of rails curvature and the center of arm 140 are disposed along an imaginary straight

center line 160 when the arm is in its *w* and *z* aspects (not shown in FIG. 5). Also in FIG. 5, abutment member 150 is twice the distance from pivot 146 as is abutment member 152; and pivot 146 is arranged for reciprocation in a course which is offset from and parallel to line 160. Accordingly, spacing of the four alternate output levels only *x* and *y* of which are illustrated by the level of the pivot will be different in FIG. 5 from the spacing of the output levels had the rails been straight, as in FIG. 1.

FIGS. 6-13 illustrate adjustments of rails 147 and 148 each relative to the other thereof and relative to output member 135. In the various views, the output member (only of which pivot 146 is shown) is disposed in its centered position; but in each view actuator arm 140 is in one of the aspects *w-z*, and the following is observed:

In FIG. 6, the solid line condition shows rails 147 and 148 shifted to the left relative center line 160; while the dashed line condition shows both rails shifted to the right thereof. Actuator arm 140 is shown in its *y* aspect. Reference to the position of pivot 146 indicates the levels of displacement of the output member corresponding to the aforesaid shifted positions of the rails.

In FIG. 7, actuator arm 140 is illustrated in its *z* aspect. Reference to pivot 146 discloses the output levels which can be effected by shifting rail 148 to the left (solid line) of center line 160 and to the right (dashed line) of the center line, while rail 147 remains centered.

In FIG. 8, rail 148 is shown shifted to the left (solid line) of the center line and to the right (dashed lines) of the center line, with actuator arm 140 being in its *x* aspect and upper rail 147 centered. By holding lower rail 148 centered (FIG. 9), a greater displacement range can be effected while arm 140 is in its *x* aspect by shifting rail 147 from left of center line 160 to the right thereof, than is effected by shifting the lower rail 148 (as in FIG. 8).

With arm 140 in the same aspect as in FIGS. 8 and 9, both rails are shown shifted (FIG. 10) to the left (solid line) of center line 160 and to the right (dashed line) thereof, such that relative to each other said rails have not moved. However, relative output member 135, they have moved together. The *x* level of displacement produced in consequence of the shift to the left from center line 160 is higher than the level resulting from shifting the rails a like distance to the right of said center line.

FIG. 11 illustrates the effect on displacement while actuator arm 140 is in its *w* aspect and rail 147 is shifted from center line 160, first to the left (solid line) and then to the right (dashed line). It is observed that while the actuator arm is in said *w* aspect, the position of rail 148 is immaterial, insofar as the effect on the level of displacement is concerned. In a similar manner, the position of rail 147 is immaterial when the actuator arm is in its *z* aspect (FIG. 7).

In FIG. 12 the rail condition depicted is the same as in FIG. 9. However, actuator arm 140 in FIG. 12 is shown in its *y* aspect. The effect on displacement of output member 135 by shifting rail 147, as in FIG. 12, is similar to the effect on displacement of the output member resulting from shifting of rail 148 when actuator arm 140 is in its *x* aspect (FIG. 8).

An effect on displacement, similar to the effect in FIG. 9, is achieved according to FIG. 13. However, in FIG. 13, actuator arm 140 is in its *y* aspect, upper rail 147 retained in its centered condition, and lower rail 148 is shown shifted from center line 160 to the left (solid line) and to the right (dashed line).

The foregoing has not taken into graphic account the relationships and effects on displacement which could result from shifting of actuator arm 140 in a path extending transversely of line 160. Nor has the effect of varying the radii of curvatures of rails 147 and 148 been illustrated graphically. However, both of these variations are within the purview of the invention as are other modifications according to displacement requirements and the design of which will occur to those skilled in the art.

Moreover, as yet other modifications in the described construction could be conceived, and as many changes could be made therein without departing from the spirit and scope of the invention, it is intended that all matter contained in the accompanying specification shall be considered as illustrative only and not in a limiting sense.

I claim:

1. An aggregate motion positioner comprising:
means defining a path;
an elongated actuator, said actuator and said path associated for relative movement;
an output member having a plurality of positions of linear displacement and pivoted off-center to said actuator;
means for rocking said actuator to displace said member linearly; and
means for limiting the lineal displacement of said member as a function of the relative location of said actuator along said path.

2. An aggregate motion positioner according to claim 1 wherein the positions of displacement of said output member are along a course intersecting said path.

3. An aggregate motion positioner according to claim 2 wherein said limiting means comprises an elongated curved stop defining said path.

4. An aggregate motion positioner according to claim 3 characterized by a pair of rails, including said stop, for limiting angular movement of said actuator when rocked.

5. An aggregate motion positioner according to claim 1 wherein said limiting means comprises a pair of rails defining said path and arranged for barring movement of the opposite end portions of said actuator to correspondingly set the level of displacement of said member.

55 6. An aggregate motion positioner according to claim 5 wherein said rocking means comprises a magnetic flux field extending longitudinally of said rails and a pair of inductive coils coupleably supported in said flux field for reversibly driving opposed end portions of said actuator.

60 7. An aggregate motion positioner comprising:
a pair of spaced apart rails defining a path;
an actuator arm having opposed end portions disposed in said path and arranged for relative movement longitudinally thereof;
a pair of abutment members connected to said opposed end portions for engaging said rails to set the aspect of said actuator arm in said path;

an output member arranged for movement along a course extending transversely of said path and pivotally connected to said actuator arm off-center from said opposed end portions; and

means for reversibly driving said opposed end portions into engagement with selected of any and both rails to adjust said output member longitudinally of its course.

8. A device according to claim 7 wherein said driving means comprises a structure for producing a magnetic flux field longitudinally of said rails and inductance means disposed in said magnetic flux field.

9. A device according to claim 8 wherein the inductance means comprises a pair of electrical coils

secured to said opposed end portions, and said structure is magnetic and has an air gap across which the lines of flux in said field extend transversely of said path.

5 10. A device according to claim 7 in which each of said rails is movably mounted relative to the other thereof and at least one of said rails has an inner curved surface adjoining said path and extending longitudinally thereof.

10 11. A device according to claim 10 characterized in that said output member and said curved surface are associated for movement, each relative to the other generally longitudinally of said rails.
